INVENTOR

UNITED STATES PATENT OFFICE

BARNETT EPSTEIN, OF NEW YORK, N. Y.

POCKETBOOK

Application filed September 24, 1929. Serial No. 394,868.

This invention relates to a pocketbook, particularly designed for the new form of currency and has for its primary object the construction of a pocketbook from a single blank of material, that is so designed that the cost of manufacture of the article is materially reduced while at the same time adding to the attractiveness of the article and its strength to resist wear.

10 An object of the invention resides in the novel manner of constructing the various sections and folding the same into parallel relation with each other to define a plurality of pockets, the sections being secured or stitched 15 at their end portions to accomplish the completion of the article.

Another object of the invention resides in the novel formation of the back section so that when the same is stitched to the associated sections the free edge portion of the back section will have a bowed formation which facilitates the insertion and removal 20 of bills and besides allows for the folding of the pocketbook into a very compact shape.

25 Besides the above my invention is distinguished in the direct forming of one or more openings in one of the sections in predetermined positions to define a group of pockets for reception of various objects.

30 A feature of the invention resides in the formation of a pocketbook in a manner that the material entering into the construction of the pocketbook may be formed at a single operation of a stamping machine and very 35 readily sketched on a stitching machine for completing the article with a plurality of pockets, certain edge portions of the pocketbook being reenforced due to the solid formation of the edges.

40 With these and other objects in view the invention will be better understood from the following detailed description taken in connection with accompanying drawings, wherein

45 Figure 1 is a perspective view of one form of the invention,

Figure 2 is a vertical sectional view on line 2-2 of Figure 1,

50 Figure 3 is a sectional view on line 3-3 of Figure 1,

Figure 4 is a plan view of the blanks,
Figure 5 is a perspective view of the blank partly folded,

Figure 6 is a perspective view of another form of the invention, 55

Figure 7 is a plan view of the blank,
Figure 8 is a perspective view of another form of the invention,

Figure 9 is a detailed sectional view through the key plate. 60

Again referring to the drawings illustrating three of the many forms of my invention, and more particularly to Figures 1 to 5 inclusive, it will be noted that the pocketbook is of one-piece construction formed from a single blank 1, the design of which is such that a large group of blanks may be cut at a single operation, thereby materially reducing production costs. The blank is of the required shape that when folded along the lines 2 and 3, a back section 4, a front section 5 and a middle section 6 is provided. Particular attention is called to the fact that the edges 7 of the back section are cut on an angle with relation to the remaining sections so that when the edge portions are stitched as indicated at 8, the back section will have a slight bowed formation to facilitate the insertion of bills and allow for the folding of the pocketbook when in use. 75

Simultaneously with the forming of a blank an opening 9 is formed in the front section which defines a pair of end walls 10 and 11 that assumes a parallel relation with the middle section for providing a pair of 85 individual pockets 12 access to which may be readily had through the opening 9. It is of course to be understood that when the back section is folded in parallel relation with the middle section, a pocket 13 is defined the opening to which is considerably reenforced by the arrangement of the solid edge portion 14 provided at the junction of the front and middle sections. Particular attention is also called to the fact that the bottom edge of the 90 pocketbook is considerably strengthened by the arrangement of the solid edge formation 15 provided at the juncture of the front section and middle section. To complete the invention I provide a plurality of clips 16 95

arranged at the corner formations of the pocketbook, not only to reenforce the same but to add to the attractiveness thereof.

Referring to Figures 4 and 5, it will be appreciated that it is a very simple operation to stamp the blank as indicated in Figure 4 and then readily fold the sections into parallel relation with each other as indicated in Figure 5, stitching the edge portions of the section by simple machine operation completing the formation of the pocketbook. Due to the formation of the various parts and mode of connection, it will be appreciated that the parts readily fold into the required position, which enables unskilled persons to very readily take advantage of quantity production at a very low production cost. Referring to Figures 6 and 7 it will be noted that the construction is practically identical with that just described with the exception that the front section 17 is provided with a pair of openings 18 defining end walls 19 and 20 and a central wall 21, which in turn is provided with a window 22. Thus it will be appreciated that I provide three individual pockets access to which may be had through the openings 18, the window 22 being provided for display purposes. If found advisable in practice, the pocketbook may be provided with fasteners 23 which secure the pocketbook in a folded position when folded from the points 24 and 25.

Figures 8 and 9 show an illustration practically identical with that described and illustrated in Figure 6 with the exception that I dispense with the window 22 and directly secure to the central wall 26 the plate 27 of a key support 28. Referring to Figure 9 it will be noted that the plate 27 is riveted to two thicknesses of material, designed by the numerals 28 through the use of the rivets 29 thereby giving greater strength to the connection and besides providing a pocket 30 below the key ring.

Although I have described three of the many forms of my invention, I wish to have it clearly understood that various other designs of pocketbooks may be obtained by somewhat changing the contour of the various sections or providing one or more of the sections with various shaped openings or windows. Therefore I am claiming broadly a one piece pocketbook formed from a single blank of material cut in a particular formation and folded along predetermined lines to provide a plurality of pockets, the pocketbook being reenforced along lines that are generally weakest in types of pocketbooks now on the market. A very important feature of my invention resides in the simplicity of construction and mode of manufacture that enables the pocketbook to be very rapidly manufactured in quantity lots at very low cost. This is accomplished by forming the sections to be

folded into parallel relation to define the pockets and finally sewing the edge portions of the sections to complete the article.

It is of course to be understood that the invention may be constructed in various other manners than illustrated and may be given other designs and shapes and therefore I do not desire to be limited in protection in any manner whatsoever except as set forth in the following claims.

I claim:

1. A one-piece pocketbook formed from a single blank of material cut to provide a middle section, a front section adapted to parallel the middle section and provided with a plurality of openings defining individual walls paralleling said middle section to provide a plurality of pockets and a back section paralleling the middle section to provide a pocket and stitching for securing the end edge portions of all of the sections together, said back section having its end edge portions out at an incline to the other section to produce a bowed effect of the back section when stitched in place.

2. A single blank for forming a one piece pocketbook consisting of a front section having a centrally arranged opening, a middle section having one edge portion formed solid with one edge portion of the front section and a back section having one edge portion formed solid with one edge portion of said front section, said back section having its end edges inclining outwardly in relation to the end edges of said front section and said middle section.

In witness whereof I have hereunto set my hand.

BARNETT EPSTEIN.
